Patented Mar. 6, 1917.

UNITED STATES PATENT OFFICE.

JOHN A. GWINNER, OF PHILADELPHIA, PENNSYLVANIA.

BOTTLE-CAPPING DEVICE.

1,218,550.

Specification of Letters Patent.

Patented Mar. 6, 1917.

Application filed August 12, 1916. Serial No. 114,567.

To all whom it may concern:

Be it known that I, JOHN A. GWINNER, a citizen of the United States, residing in Philadelphia, Pennsylvania, have invented 5 certain Improvements in Bottle-Capping Devices, of which the following is a specification.

My invention relates to bottle capping machines; and the object of my invention is to 10 provide a device for applying a special form of cap of the "crown" type, which special cap is provided with a laterally extended projection forming self-contained means whereby the cap may be removed from the 15 bottle.

These and other features of my invention are more fully described hereinafter, reference being had to the accompanying drawings, in which:

20 Figure 1, is an inverted plan view of the structure forming the subject of my invention.

Fig. 2, is a sectional elevation on the line II—II, Fig. 1, showing also the parts supporting the capping throat.

Fig. 3, is a sectional elevation on the line III—III, Fig. 1.

Fig. 4, illustrates a modified structure within the scope of my invention.

30 Fig. 5, is a sectional view of the special cap before placement upon a bottle.

Fig. 6, is a sectional view illustrating the special cap in position upon the head end of a bottle.

35 Fig. 7, is a plan view of the special cap, and

Fig. 8, is a view similar to Fig. 5, illustrating a special arrangement of the projection of the special cap before undergoing 40 the capping operation.

The "crown" cap of commerce is well known, and its mode of application is also a matter of common knowledge, but the usual "crown" cap is of such a character that 45 it must be removed by special means, usually a tool with a claw designed to engage the flange and lift it off the bottle neck.

Caps have been provided with laterally extended projections whereby they form 50 self-contained means to lift the cap from its seat on the bottle neck, but with the means heretofore employed it has been difficult, if not impossible, to seat these caps upon the bottle necks, and the object of my invention 55 is the provision of means whereby the special

"crown" caps, such as illustrated in Figs. 5, 6, 7 and 8, may be applied to bottle necks.

The general method of operation is substantially similar to that carried out in the use of the structure illustrated in the U. S. 60 patent of Painter, No. 473,776, dated April 26, 1892, and the feature of my invention will be more particularly pointed out hereinafter in connection with the accompanying drawings.

In Fig. 1, 1 represents a stationary sleeve carried by the mechanism of the character above referred to, having a plurality of dogs 2 set in slots 3, and supported by means of springs 4, as illustrated, in position to engage and support a cap 5 when the same is introduced into position; such sleeve having a through tapered passage 6 for the capping plunger 7, and being cut away at 8 for the passage of the laterally extended tab or projection 5^a of the special cap.

The dogs are provided with springs whereby they are automatically projected inwardly to support the caps in position; such dogs being automatically moved out of the 80 way by the neck of the bottle as the latter is introduced into the capping sleeve. The wall of the passage in said capping sleeve is tapered so that as the bottle with its superposed cap is pushed into the same by the 85 means usually employed for the purpose, the tapered walls of said sleeve passage will act upon the corrugated flange of the cap and press down the points of the same so as to cause the wall portions between the points 90 to pass under the flange of the bottle neck or head in the manner illustrated in Fig. 6. It will be noted that the projection or tab of the cap is provided with corrugations in line with those of the flange to stiffen and 95 protect the same.

In order to insure proper engagement of the cap adjacent the lateral projection of the same, the tapered wall of the sleeve passage may be specially shaped as indicated at 8^a in 100 Fig. 1, whereby an extra pressure may be applied to the cap flange at the points z, Fig. 7, adjacent its junction with the lateral projection or tab 5^a.

The engagement of the tapered wall of the 105 through passage of the sleeve with the flange of the cap causes the latter to grip the bead at the head or neck end of the bottle; thereby holding the cap in sealing position. The clamping or pressing action applied to such 110

flange adjacent the tab or projection 5^a tends to cause the tab to depress or incline downwardly at its outer end. While this is not objectionable in most instances, it may be compensated for by having the tab or projection bent up slightly before it is applied to the bottle neck, as shown at 5^b in Fig. 8.

In some instances, the clearance space for the lateral projection or tab of the special 10 cap need not extend entirely through the sleeve, and in Fig. 4, I have illustrated such an arrangement, in which a recess 8^b is provided to accommodate the tab or projection.

I claim:

15 1. In a device for bending flanged sealing caps having a laterally projecting tab into locking contact with the heads of bottles, the combination of a capping socket having a passage with a tapered wall, a longitudinally movable cap plunger in said socket, 20 20 flange of said cap adjacent its junction with the laterally extended projection or tab.

said socket having a clearance space at one side for the free reception of the laterally extended projection or tab of the cap, and provision for additionally crimping the flange of said cap adjacent its junction with 25 the laterally extended projection or tab.

2. In a device for bending flanged sealing caps having a laterally projecting tab into locking contact with the head of a bottle, the combination of a capping socket having a passage with a tapered wall, a longitudinally movable cap plunger in said socket, 30 said socket having a through space at one side of the tapered-wall passage for the free reception of the laterally extended projection or tab of the cap, and provision for additionally crimping said cap at the junction of the laterally extended projection or tab and the flange of the same.

JOHN A. GWINNER.
